[57] **CLAIM**

The ornamental design for a pennant windsock, as shown and described.

DESCRIPTION

FIG. 1 is a perspective view of a pennant windsock embodying the new design;

FIG. 2 is a side elevational view taken from one side, thereof;

FIG. 3 is a top plan view thereof, the bottom being substantially identical;

FIG. 4 is an end elevational view thereof taken from one end; and

FIG. 5 is an end elevational view thereof taken from the other end.

The supporting post is shown broken away to indicate indeterminate length. The broken lines represent conventional stitching and the cross-line shading represents a conventional fabric.
